1 Claim

The present invention comprises a new and distinct cultivar of standard form chrysanthemum plant known by the varietal name Colonel Comfort. The new cultivar is a sport of the well known non-patented cultivar known in the United States as Southern Comfort.

The new cultivar is similar in many respects to Southern Comfort, having the same characteristics of:

1. Ivory flower color.
2. Sharp and reliable response at temperatures above 70°.
3. Similar foliage shape, color and form.
4. Similar recommended flowering period.

The new cultivar is distinguished from Southern Comfort by the following characteristics when grown under comparable conditions:

1. A flower approximately 1" to 1½" larger in diameter.
2. Based on Society of American Florists grading standards, it grades out with a higher percentage of flowers in the top two grades.
3. A more incurved flower form.
4. Approximately 2-3 days later response.
5. An improved form retention which provides longer bench life.
6. Foliage approximately ½" longer in length and ½" greater in width.

Botanical classification: *Chrysanthemum morifolium*

	Colonel Comfort	Southern Comfort
Bloom:		
Size.....	6½"	5"-5½".
Grade Data: Averaged Percentages for a Summer's Flowering Performance in 1972 at Barberton, Ohio, (based on Society of American Florists Grade Standards)		
	Blue	Red
Colonel Comfort.....	56%	32%
Southern Comfort.....	35%	41%
	Green	Culls
	Colonel Comfort	Southern Comfort
Bloom (contd.):		
Fully expanded.....	7"-7½"	6".
Borne.....	Singly on disbudded plant.	
Stems.....	Strong.	
Form.....	Semi-incurve.....	Semi-incurve but to a lesser degree.
Permanence.....	12-14 days.....	8-12 days.
Color:		
Center of flower.....	Yellow-green, 1.25 G Y8/12 to yellow, 10 Y8/12.....	
Base of petals.....	Yellow, 10 Y8/12.....	
Inside of petals.....	Ivory, 10 Y9/2 to ivory, 10 Y9/1.....	
Reverse of petals.....	Ivory, 10 Y9/1.....	
Tonalism from a distance.....	Ivory white.....	
Discoloration.....	Ivory, 10 Y9/1.....	
Petals:		
Texture.....	Smooth.....	
Appearance and form.....	Closed at base, flaring quickly to a smooth rounded keel tapering to a notched blunt tip.	
Arrangement.....	Composite, whorled on a single receptacle.....	
Persistence.....	Resist shatter.....	
Fragrance.....	Typical chrysanthemum.....	
Reproductive organs:		
Stamen, anthers.....	None.....	
Pollen.....	do.....	
Arrangement.....	Clustered in center of flower, if present.....	
Styles.....	Present in ray florets.....	
Length.....	Short.....	
Ovaries.....	At the base of petal attached to receptacle.....	
Plant:		
Form.....	Herbaceous.....	
Growth.....	Upright.....	
Height.....	Approximately 46"-54" given 2 long day weeks, and 11 week total crop time as defined in the timetables of Yoder Brothers, Inc., Barberton, Ohio, for the various seasons of the year.	Approximately 46"-54" given 2 long day weeks, and 11 week total crop time as defined in the timetables of Yoder Brothers, Inc., Barberton, Ohio, for the various seasons of the year.
Spread.....	None grown single stem.....	

TABLE—Continued

	Colonel Comfort	Southern Comfort
Foliation:		
Top side.....	Dark green, 7.5GY2/4.....	
Size.....	Length to width ratio 3/2 with foliage up to 6" long and 4" wide.	Length to width ratio 11/7 with foliage up to 5½" long, and 3½" wide.
Quantity.....	Numerous.....	
Shape.....	Spatulate lobed.....	
Texture.....	Coarse.....	
Ribs and veins.....	Prominent.....	
Edge.....	Indented.....	
Serration.....	Moderate.....	
Under side.....	Medium green, 7.5GY4/4.....	
Stipules.....	Prominent.....	

We claim:

1. A new and distinct cultivar of chrysanthemum characterized particularly as to uniqueness when compared to the parent cultivar Southern Comfort by its flower which is approximately 1"-1½" larger in diameter; by its superior grade performance, grading out with a higher percentage of flowers in the top two grades; approximately 3" to 4" more vigor; a more incurved

15 flower form; approximately 2-3 days later response; improved form retention which provides longer bench life, and by its foliage which is approximately ½" longer in length and ½" greater in width.
